PINCUSHION

Arthur T. Moeglich, Jackson Heights, N. Y.

Application April 24, 1953, Serial No. 24,658

Term of patent 14 years

(Cl. D3—19)

To all whom it may concern:

Be it known that I, Arthur T. Moeglich, a citizen of the United States of America, residing at Jackson Heights, county of Queens, and State of New York, have invented a new, original, and ornamental Design for a Pincushion, of which the following is a specification, reference being had to the accompanying drawing, forming a part thereof.

The back of the pincushion is plain and unornamented.

I claim:

The ornamental design for a pincushion, as shown and described.

ARTHUR T. MOEGLICH.
